UNITED STATES PATENT OFFICE

ALBERT E. EVANS, OF PITTSBURGH, PENNSYLVANIA, ASSIGNOR TO PITTSBURGH PLATE GLASS COMPANY, A CORPORATION OF PENNSYLVANIA

UNCOUPLING DEVICE

Application filed January 21, 1930. Serial No. 422,455.

The invention relates to a car transfer system designed particularly for handling the cars or tables employed in what is known as a straight away plate glass grinding and polishing operation. It has for its objects the provision of improved means for facilitating the shifting of the cars between a plurality of parallel tracks and for controlling the coupling and uncoupling of the cars by the operator of the shifting locomotive.

In the particular arrangement to which the improvement is applied, four parallel tracks are employed, the two central tracks being work tracks passing beneath a series of grinding and polishing runners, and the two outside tracks being return tracks for bringing the grinding tables or cars back to starting position on the work tracks. At each end of the four tracks is a transverse track carrying a transfer car, and upon the car is mounted a locomotive for pulling the grinding cars onto the transfer car and then pushing them off. A means is thus provided at each end of the four tracks for shifting the cars from any one of such tracks to any one of the other of such tracks. The improvement relates particularly to the means at the end of the working tracks and on the locomotive whereby the operator on the locomotive can secure the disengagement of the end car from the next car preliminary to pulling such end car onto the transfer car. One embodiment of the invention is illustrated in the accompanying drawings, wherein:

Figure 1 is a side elevation somewhat diagrammatic in character showing the parts preliminary to causing the shifting locomotive to make coupling engagement with the end car of the train. Fig. 2 is a view similar to that of Fig. 1 after the locomotive has been moved into coupling relation with said end car. Fig. 3 is a view similar to that of Figs. 1 and 2 after the uncoupling device has moved to one extreme of movement. Fig. 4 is a plan view of the apparatus positioned as in Fig. 2, but with the cars removed. And Fig. 5 is a section on the line V—V of Fig. 3.

Referring to the drawings, 1 is the track for the work cars, the end cars of which 2 and 3 only are shown, such cars being moved

slowly to the left (Figs. 1 to 4) by any suitable means, such as the racks 4 (Fig. 5) driven from suitable pinions (not shown). Extending transversely of the work track is the transfer track 5 upon which is mounted the transfer car 6. This car is provided with a track 7 adapted to line up with the track 1, such track carrying the transfer locomotive 8. Each of the cars 2, 3 is provided at its left hand end with a swinging coupler hook 9 operated from a transverse shaft which carries at each end at the side of the car an operating lever 10, the coupling mechanism being similar to that shown in the Evans application, Serial No. 412,210, filed December 6, 1929, and requiring no detailed description. It is sufficient to say that when the lever is in the position shown in Fig. 1, the swinging coupler hook 9 is in locked or engaging position, and that when it is swung to the left about 90 degrees, the hook 9 is raised, thus detaching it from the hook on the next car, each car being provided on its right hand end with a fixed hook, facing upward, with which the downwardly facing hook 9 is adapted to be engaged.

The locomotive is provided with an upwardly facing coupler hook 11 forming the end of the lever 12 pivoted at 13 and operated by means of the rod 14 secured at its upper end to the pedal 15. This coupling hook is normally held in uncoupled position by means of the spring 16 and is brought to coupled position by the operator seated on the chair 17 when he presses his foot downward. The locomotive is provided at its sides with a pair of links 18 mounted for sliding movement and provided with the down-turned ends 19. These links are operated by means of bell crank levers 20 pivoted at 21 and connected to cranks 22 by means of connecting rods 23. The cranks 22 are carried upon a transverse shaft 24 driven from a motor 25 through the intermediary of suitable worm reduction gearing in the casing 27. The links 18 may in this manner be driven back and forth by the rotation of the shaft 24 and serve to perform the uncoupling operation at the end of the car 2 which is farthest removed from the locomotive.

The levers 10 are operated from the links 18 through the intermediary of devices mounted for longitudinal movement at the sides of the track 1 and referred to hereinafter as "sleds". These devices comprise longitudinally extending plates 28 provided at their ends with carriages 29 and 30 mounted upon the rollers 31 and 32. These rollers are carried upon tracks or guides in the form of the beams 32a which extend for a considerable distance along the sides of the track 1, such means terminating at their left-hand ends in inclined parts or cams 32b which perform a function later explained.

The carriages 30 at the right-hand end of the sleds are provided with bell crank levers 33, whose short ends are connected to rods 34 extending through the flanges 35 carried by the plates of the carriages 30. Springs 36 surrounding such rods are interposed between the flanges 35 and nuts 37 on the rods so that the levers 33 are yieldingly held in the position shown. These levers have their ends 38 turned inward, as indicated in Fig. 5, thus adapting them to interlock with the levers 10 when the carriage is moved to the right to the position indicated in Fig. 3. In moving to this position, the lever 33 must, of course, swing downward in order to pass the lever 10, which movement is permitted by reason of the springs 36, which allow the ends 38 to slide past the levers 10 to the position shown in Fig. 3. When the sleds are now moved to the left from the position of Fig. 3, the ends 38 of the levers 33 engage the levers 10 and swing them to the left to unlocking position.

The carriages 29 at the left-hand ends of the sleds are provided with bumpers 39 supported by the springs 40 and adapted to be engaged by the down-turned ends 19 of the links 18 when these members are moved to the right. After the locomotive has been coupled to the end car 2, the movement of the sleds to the right to the position of Fig. 3 and then back to starting position, as indicated in Fig. 2, unlocks the coupler between the cars 2 and 3 so that the locomotive is free to move to the left, pulling the car 2 with it onto the transfer table 6.

In order to permit the link 18 to pull the sleds to the left, the angular latches 41 are provided upon the carriages 29. These latches are provided with rollers 42 lying over the tops of the beams 32a when the sleds are in the position shown in Fig. 2. At such time the vertical arms of the latches lie behind the down-turned ends 19 of the links 18 so that when the ends 19 are moved to the left, the sled is dragged to the left to perform the unlocking function. When the sleds are moved far enough to the left, so that the rollers 42 ride down on the inclines 32b, the latches 41 are released from the ends 19, thus complete-

ly detaching the locomotives from the sleds, this condition being shown in Fig. 1.

The operation is as follows, starting with the apparatus in the position shown in Fig. 1. The locomotive 8 moves to the right from the position shown, so that the hook 11 is engaged with the coupler hook on the end car 2, thus bringing the parts to the position shown in Fig. 2. During this movement, the ends 19 of the links 18 engage the bumpers 39 on the sleds and push them to the right to the position shown in Fig. 2. This movement to the right causes the rollers 42 on the latches 41 to ride up over the inclines or cams 32b, thus bringing the ends of the latches up behind the ends 19, as indicated in Fig. 2. The motor 25 is now operated to cause the movement of the links 18 to the right, this movement carrying the sleds to the right to the position indicated in Fig. 3 with the levers 33 in interlocking relation with respect to the coupler levers 10. The continued operation of the motor 25 swings the links 18 to the left, thus moving the sleds to the left to the position indicated in Fig. 2 and bringing the coupler levers 10 to the position indicated in Fig. 2, thus unlocking the coupling at the ends of the cars 2 and 3. The unlocking operation is now completed and the locomotive is free to move to the left, dragging with it the car 2. By the time this car is taken away and transferred to another track, and the locomotive is returned to its starting position, as shown in Fig. 1, the next work car has been moved along by the train to the end of the track 1 so that the parts are in position for a second operation the same as above described.

What I claim is:

1. The combination of a transfer system including a track and a train of work cars thereon provided with couplers at their ends and swinging levers at the sides of the cars for operating the couplers; of a shifting locomotive provided with a coupler for engaging the coupler at the free end of the end car of said train, and means operable from the locomotive for swinging the operating lever of the coupler at the forward end of the second car to release such coupler and free said end car from the train, said means comprising a sled extending along said track and mounted for limited movement longitudinally of the track, means on the end of the sled remote from the locomotive for engaging said lever, and means carried by the locomotive for engaging the other end of the sled and moving it to cause it to swing said lever to unlocking position.

2. The combination in a transfer system including a track and a train of work cars thereon provided with couplers at their ends and swinging levers at the sides of the cars for operating the couplers; of a shifting locomotive provided with a coupler for engaging

the coupler at the free end of the end car of said train, and means operable from the locomotive for swinging the operating lever of the coupler at the forward end of the second car to release such coupler and free said end car from the train, said means comprising a sled extending along said track and mounted for limited movement longitudinally of the track, means on the end of the sled remote from the locomotive for engaging said lever, and means carried by the locomotive for engaging the other end of the sled and reciprocating it so that during one movement said means at the remote end of the sled are caused to engage said lever, and during the reverse movement are caused to move the lever to unlocking position.

3. The combination in a transfer system including a track and a train of work cars thereon provided with couplers at their ends and swinging levers at the sides of the cars for operating the couplers; of a shifting locomotive provided with a coupler for engaging the coupler at the free end of the end car of said train, and means operable from the locomotive for swinging the operating lever of the coupler at the forward end of the second car to release such coupler and free said end car from the train, said means comprising a sled extending along said track and mounted for limited movement longitudinally of the track, means on the end of the sled remote from the locomotive for engaging said lever, an abutment at the other end of the sled, a pivoted latch on the sled to the rear of said abutment, a link mounted on the locomotive for movement longitudinally of the track and having a depending end adapted to engage said abutment, means on the locomotive for reciprocating the link and a cam member for moving the latch to operative position behind said depending end and holding it there until said link is moved to the rear far enough to cause the sled to swing said lever to uncoupling position.

4. The combination in a transfer system including a track and a train of work cars thereon provided with couplers at their ends and swinging levers at the sides of the cars for operating the couplers; of a shifting locomotive provided with a coupler for engaging the coupler at the free end of the end car of said train, and means operable from the locomotive for swinging the operating lever of the coupler at the forward end of the second car to release such coupler and free said end car from the train, said means comprising a sled extending along said track and mounted for limited movement longitudinally of the track, means on the end of the sled remote from the locomotive for engaging said lever, an abutment at the other end of the sled, a pivoted latch on the sled to the rear of said abutment, a rail having an inclined end located beneath the line of move-

ment of the sled and adapted to hold the latch in its upper position while the latch lies above such rail, but permits the latch to move down when the latch passes off of said inclined end, a link mounted on the locomotive for movement longitudinally of the track with a depending end adapted to lie between said abutment and latch and to engage the abutment on the forward movement of the link and to engage said latch on the rearward movement of the link, and means on the locomotive for reciprocating said link.

In testimony whereof I have hereunto subscribed my name this 31st day of December, 1929.

ALBERT E. EVANS.
